(57) **CLAIM**

The ornamental design for a charger, as shown and described.

DESCRIPTION

FIG. 1 is a first perspective view of a charger showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is atop view thereof;

FIG. 8 is a bottom view thereof; and,

FIG. 9 is a perspective view of another state of the charger thereof.

The broken lines shown in the drawings depict portions of the charger in which the design is embodied that form no part of the claimed design.
